(57) **CLAIM**

The ornamental design for a compensation nut assembly, as shown and described.

DESCRIPTION

FIG. 1 is an isometric view of a front, top, and left side of an ornamental design for a compensation nut assembly; FIG. 2 is a front elevational view of the compensation nut assembly of FIG. 1; FIG. 3 is a rear elevational view of the compensation nut assembly of FIG. 1; FIG. 4 is a left side elevational view of the compensation nut assembly of FIG. 1; FIG. 5 is a right side elevational view of the compensation nut assembly of FIG. 1; and, FIG. 6 is a top plan view of the compensation nut assembly of FIG. 1.

The broken lines represent portions of the structure that forms no part of the claim. The dash-dot-dash lines define a boundary of the claim.
